DISPOSABLE IRRIGATION CONTAINER OR THE LIKE

Elias Picker, Kew Gardens, N.Y., assignor to Ipeo Hospital Supply Corporation, New York, N.Y., a corporation of New York

Filed Oct. 31, 1962, Ser. No. 72,319

Term of patent 14 years

(Cl. D83—1)

FIG. 1

FIG. 2

FIG. 3

I claim:

The ornamental design for a disposable irrigation container or the like, as shown.
